CLAIM

The ornamental design for a tap, as shown and described.

DESCRIPTION

FIG. 1 is a front elevation view of a tap with an R-groove used for the tapping and/or forming a thread in a hole in accordance with my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof taken from the bottom, front and right side of the tap.
